UNITED STATES PATENT OFFICE.

EDWARD T. BIRDSALL, OF NEW ROCHELLE, NEW YORK, ASSIGNOR TO
DESERON MOTOR CAR COMPANY, OF NEW YORK, N. Y.

MOTOR-VEHICLE.

SPECIFICATION forming part of Letters Patent No. 684,535, dated October 15, 1901.

Application filed July 29, 1901. Serial No. 70,028. (No model.)

To all whom it may concern:

Be it known that I, EDWARD T. BIRDSALL, a citizen of the United States, residing at New Rochelle, in the county of Westchester and 5 State of New York, have made a new and useful Invention in Motor-Vehicles, of which the following is a specification.

My invention relates to improvements upon motor - propelled vehicles designed for use 10 upon common roads, and particularly to that type of road-wagons known as "commercial vehicles," such as are used for the transportation of merchandise and passengers; and it has for its objects, first, to do away with 15 what is known as the "reach" in this class of vehicles—such, for instance, as is commonly used with wagons or carriages drawn by horses and also has been to some extent in use in connection with motor-vehicles, and, second, 20 to so arrange the entire structure that the "change-gear" apparatus and driving mechanism directly attached to the main axle shall be flexibly connected to each other, so that the action of the springs and the twisting of the 25 main frame of the vehicle shall have no tendency to cause any of the bearings to bind or in any manner create undue friction. These several objects are accomplished in the use of the machine hereinafter described, and for 30 a full and clear understanding of which, such as will enable others skilled in the art to construct and use the same, reference is had to the accompanying drawings, in which—

Figure 1 is a side elevational view of a complete motor-vehicle embodying my improvements, and Fig. 2 is a plan view of the major portion thereof as seen looking at Fig. 1 from the top toward the bottom of the drawings. Fig. 3 is a part-elevational, part-sectional view 40 of my novel means for flexibly or yieldingly supporting or suspending the driving-gear mechanism and its surrounding case, the major portion of which parts are pivotally supported directly by the axle. Fig. 4 is a plan view of the parts illustrated in Fig. 3 as seen looking thereat from the top toward the bottom of the drawings, the side bars of the frame, however, being omitted in this view. Fig. 5 is a sectional view taken through Fig. 4 on 45 the line $\alpha\alpha$. Fig. 6 is a side elevational view upon a smaller scale, illustrating the manner

of suspending the supporting gear-casing in a modified manner, the link which connects the casing to the frame of the machine in this instance being attached at its lower end to 55 the extreme outer or free end of said supporting-casing.

Referring now to the drawings in detail, e represents the driving-axle, and $w w' w'$ the wheels of the machine, $a a$ being iron T-rails 60 constituting the side bars of the frame, and $a^3 a^3$ angle-irons constituting the cross-bars properly braced at their opposite ends and secured by bolts directly to the side bars, a^2 being a similar longitudinal angle-iron properly braced at its opposite ends between the cross-bars $a^3 a^3$ and located parallel with the side bars $a a$.

d is a third cross-bar braced at its opposite ends and secured between one of the side 70 bars a and the parallel angle-iron a^2 and acting as a support for the rear end of the engine u —in the present instance a steam-engine—the front end of which is directly supported by the front cross-bar a^3 . 75

$s' s' s'$ represent the springs of the vehicle, and $b c$ the boiler box or cover.

g represents the master gear-wheel of the driving-gearing, connected to the axle e by the usual form of differential gearing inclosed 80 in a casing c' , said differential gearing being preferably connected directly to the axle by any well-known form of spring or other means for yieldingly transmitting the power to the axle e when suddenly applied. 85

c is an exterior supporting-casing adapted to act also as a dust-guard and oil-reservoir for the differential and connecting gears. This casing is pivotally supported upon the axle with the gearing, and the free end thereof 90 is provided with separable journal-bearings $i m$, located in alinement with the main driving-axle, said journal-bearings being for the purpose of supporting the outer end of a flexible line of shafting e' , made flexible by 95 universal joints $j j$. To the outer end of the frame is secured a link l , preferably of U form, (see Fig. 3,) its upper end being provided with a screw-neck n and a ball-and-socket bearing, the ball part b thereof being 100 adapted to move freely in a socket s between the two parts of a metallic block f , secured

by bolts b^3 b^5 to metallic channel-irons a' a' , the outer ends of which are separated by metallic blocks o o , which are secured by bolts b^2 b^2 b^3 , passing through the channel-irons, the outer ends of said channel-irons being in turn secured directly to the side bars a a of the frame by bolts b' b' , the arrangement being such that when all of the parts are in position, as shown, the free or movable end of the flexible line of shafting e' is adapted to partake of any movement to which the vehicle may subject it and yet not vary the working relations between the driving-pinion carried thereby and the master-wheel g , this feature constituting one of the essential elements of my invention.

g' g^2 and p p' constitute the change-gear apparatus, of well-known form, the gear-wheels g' g^2 being carried directly by the flexible line of shafting e' , and the pinions p p' adapted to be moved in and out of gear in a well-known manner.

k is the clutch connecting the engine directly with the shaft e^2 , said clutch being of usual form and of such a nature as to yield sufficiently to prevent undue strains upon the shaft.

r is the brake-rod, operatively connected with the necessary lever carried by the axle e (see Fig. 1) and additional branch brake-rods r^2 r^2 and brake-rod b^4 , carrying brake-shoes bs bs , these matters being of well-known form.

In the modified form shown in Fig. 6 the lower end of the link l is secured directly to an extension of the free end of the supporting-casing, which extension may be of any length, dependent, of course, upon the flexibility of the line of shafting e' .

Although I have shown my invention as applicable to motor-vehicles propelled by a steam-engine, I wish it understood that the essential features thereof are applicable in connection with all types of motor-vehicles—such, for instance, as are driven by gasolene-engines and electric motors—or in connection with such sources of motive power as will naturally suggest themselves to the builder and user, and I desire it understood that my claims are to be construed as of such scope as to include all such vehicles.

Having thus described my invention, what I claim, and desire to secure by Letters Patent of the United States, is—

1. In a motor-vehicle the combination of the driving-wheels operatively connected to the

driving-gearing, said gearing being inclosed in an oil and dusttight supporting-casing; together with a universally-jointed link adapted to support said casing at one end from the main frame of the vehicle, substantially as described.

2. A motor-vehicle provided with driving-wheels connected to the main driving-axle, a power-transmitting device carried by the main axle consisting of a differential and suitable gearing for driving the differential, said parts being all inclosed in an oil and dust tight supporting-casing; in combination with a universally-jointed link connecting one end of the casing with the main frame of the vehicle, substantially as described.

3. A motor-vehicle having a main driving-axle, a supporting-casing free to revolve upon said axle and containing the differential and its driving-gear, the front end of said supporting-casing being connected to a universally-jointed link, which in turn is connected to the main frame of the vehicle, substantially as described.

4. In a motor-vehicle the combination of an engine, a clutch or coupling, a "change-gear" mechanism, a universally-jointed connecting-shaft, a casing supported and free to revolve upon the main axle and flexibly connected to the main frame of the vehicle, substantially as described.

5. A motor-vehicle having driving-gearing pivotally supported upon one of the axles of the vehicle; together with a pinion meshing with the master-wheel of said driving-gearing, said parts being inclosed in a supporting-casing adapted to partake of movement with the gearing about the axle, the opposite ends of the shaft which supports the pinion having journal-bearings in the supporting-casing, said casing being in turn attached to a link the upper end of which is connected by ball-and-socket joint to the main frame of the vehicle, one end of the shaft which supports the pinion being connected by a flexible line of shafting with "change-gear" mechanism operatively connected with the driving-motor, substantially as described.

In testimony whereof I have signed my name to this specification in the presence of two subscribing witnesses.

EDWARD T. BIRDSALL.
